(57) **CLAIM**

The ornamental design for an ice bucket and lid, as shown and described.

DESCRIPTION

FIG. 1 is a perspective view from slightly above the ice bucket and lid of the present invention.

FIG. 2 is a first side elevation view of the ice bucket and lid of FIG. 1.

FIG. 3 is a second side elevation view of the ice bucket and lid taken at a 90 degree azimuth angle to the view in FIG. 2.

FIG. 4 is a top plan view of the ice bucket and lid of FIG. 1.

FIG. 5 is a bottom plan view of the ice bucket of the present invention; and,

FIG. 6 is a view similar to that of FIG. 1, except with the ice bucket and lid separated in an exploded view.
